Pennie Davis Marvin Edmunds

UNITED STATES PATENT OFFICE.

JOHN CHARAVELLE INGRAM, OF CHICAGO, ILLINOIS, ASSIGNOR TO THE AMERICAN COTTON OIL COMPANY, OF NEW YORK, N. Y., A CORPORATION OF NEW JERSEY.

FINELY-DIVIDED SOAP AND METHOD OF MANUFACTURING THE SAME.

Application filed August 11, 1920. Serial No. 403,896.

To all whom it may concern:

Be it known that I, JOHN C. INGRAM, a citizen of the United States, residing at Chicago, in the county of Cook, State of Illinois, have invented certain new and useful Improvements in Finely-Divided Soap and Methods of Manufacturing the Same; and I do hereby declare the following to be a full, clear, and exact description of the invention, such as will enable others skilled in the art to which it appertains to make and use the same.

This invention relates to an improved soap powder and to an improved method of making the same by an atomizing or spraying operation. The invention also relates to an improved method of aerating and of drying soap for the production of an aerated or a dried, or a combined aerated and dried, product.

In the common soap making operations, the hot molten soap is poured in frames or molds and is permitted to cool and solidify, an operation which may require several days for its completion. The soap is then cut into slabs and finally into bars, which are dried before the soap is finally formed into cakes and pressed. If the soap is to be used for making a milled soap, the semi-dried bars are subjected to a chipping operation, the chips are then further dried, and are then subjected to the milling and plodding operations, after which the soap is pressed into cakes.

When soap is converted into a powder by mechanical means, it must be dried to the proper degree before such chipping or pulverizing can take place, if a dry and non-sticking powder is to be produced, inasmuch as soap which is moist will stick together and retard or prevent the production of the desired powder or chips.

The present invention is based upon the discovery that an improved form of soap powder, having a relatively large moisture content, and adapted to be rapidly and completely dissolved, can be readily produced from hot molten soap by an atomizing or spraying operation. The present invention is based upon the further discovery that hot molten soap can, by an atomizing or spraying operation with compressed air, be converted into an aerated, floating product.

The invention includes the further discovery that soap can be rapidly and efficiently dried and converted, from a hot molten state, to the form of a relatively dry powder, by a combined atomizing and drying operation. The present invention thus includes improvements in the drying of soap, in the aerating of soap, and in the production of an improved aerated and floating soap powder of high moisture content well adapted for rapid and complete solution in water. The soap powder of the present invention may thus contain 20% or more of moisture, but the soap particles, due to the method of their production, are provided with an outer surface or layer dried to such an extent as to prevent objectionable sticking together of the particles.

According to the present invention, soap, while in a hot molten state, is subjected to a combined spraying and aerating operation, whereby the soap is atomized or disintegrated and simultaneously aerated, and thereby converted into the form of a granulated or shredded or finely divided aerated soap. In carrying out the combined disintegrating and aerating operations the soap can also be dried, by the same operation, so that the finely divided aerated soap is directly produced in a dry state. In the preferred embodiment of the invention, the disintegrating and aerating operations are carried to such an extent that the soap powder is a floating powder although the advantages of the invention can be secured to a lesser extent if the aeration is not carried sufficiently far to give a completely floating product.

The present invention relates more particularly to the treatment of high grade soaps, of relatively high purity, such as are used for toilet and like purposes, for the production of a finely divided, aerated and dried product. The conversion of the soap paste, which contains an amount of water in excess of that desired in the completed soap, is advantageously effected by the combined atomizing and drying operations of the present invention, and the moisture content can thus be reduced to a sufficient degree to prevent objectionable sticking together of the resulting fine particles, while nevertheless leaving a suffi-

ciently high percentage of moisture in the soap powder to permit rapid and complete solution. According to the present invention, the molding, cooling, drying and other operations commonly heretofore practiced for the treatment of hot molten soap, are obviated, or gradually shortened and simplified, inasmuch as the process of the present invention can be practiced to give directly a dry, aerated soap powder.

The soap powder produced according to the present invention may itself be used as a soap powder, or it may be used for the manufacture of soap comparable with milled soap. When the soap powder is to be used as such, it presents the important advantages of floating, because of its aeration, and of being rapidly dissolved, so that the user is insured of the complete solution of all of the soap added, and can ascertain when such solution is completed, merely by observing when all of the floating powder has disappeared.

The hot molten soap employed in the process of the present invention may be soap that has been subjected to the usual crutching operations for the incorporation of the usual ingredients, perfume, etc., and the soap may likewise be subjected to a greater or less extent to aeration during the crutching operation. It is a characteristic advantage of the invention, however, that this crutching operation can be eliminated, in many cases, and the hot molten soap taken directly from the kettle, without crutching, and subjected to the disintegrating, aerating, and drying operations, for the direct production of an aerated soap powder.

The invention will be further described in connection with the accompanying drawing, showing one form of apparatus adapted for the practice of the invention.

In the accompanying drawing, Fig. 1 shows in a somewhat conventional and diagrammatic manner an arrangement of apparatus adapted for the practice of the invention; Fig. 2 is an enlarged view of one form of nozzle.

In the apparatus illustrated, a suitable supply tank for the hot molten soap is indicated at 1. It may be provided with a slow moving mixer consisting of a number of blades fastened to the horizontal shaft. It is connected at its bottom by a suitable valve controlled pipe with the pump 3 by which the molten soap is forced to the atomizing nozzle 4. A compressed air tank 3 is likewise connected through a pipe, having an air controlling valve 5 therein, with the spray nozzle 4. A pressure gauge is arranged to show the pressure in the nozzle so that the blowing or atomizing operation can be suitably regulated and controlled. The flow of soap is regulated by the soap valve 6

arranged near the nozzle and operated by a handle extending through the wall of the atomizing chamber.

The atomizing nozzle 4 is arranged within a large vertical chamber which is supplied with a current of air by means of the fan or blower 8 which discharges through the passage 9 and the opening 10 into the blowing tower. The temperature of the air can be regulated, by suitable heating means, if desired, to promote the drying operation.

In the operation of the apparatus, the hot molten soap is compounded, if desired, with suitable admixtures, such as fillers, colloidal clay, etc., or taken directly from the soap kettle, and is supplied to the tank 1. The soap paste can be aerated in the supply tank by beating in air or by treatment with air under pressure during the mixing operation. So also, further amounts of air can be incorporated in the pumps 3 and the soap thereby aerated before it is atomized, and the atomizing operation correspondingly promoted.

Compressed air from a suitable source is passed through the air pressure tank 2, where equalization of pressure takes place and where condensed moisture will be trapped, and the compressed air is supplied from this tank to the atomizing nozzle at a suitable pressure of e. g. 25 to 75 pounds per square inch, depending upon the size and construction of the atomizing nozzle, etc.

One suitable form of atomizing nozzle is illustrated in Fig. 2 and is made up of the T 11 to which the air pipe 12 and soap pipe 13 are connected. The discharge is through a spray head 14, of restricted size, but nevertheless of sufficient size to substantially prevent danger of clogging of the nozzle. The molten soap is forced into the spray nozzle against a vertical stream of air entering from the top and the soap is blown down through the nozzle against the splash disc 15 and is thereby broken up into comparatively small particles and simultaneously aerated. The pressure of the air and the supply of soap are so regulated that the operation is continuous and the desired degree of subdivision is effected.

The action which takes place in the nozzle illustrated is, as I believe, a jetting action, due to a rapid and intermittent forcing of minute pistons of molten soap outwardly through the nozzle by the air jet, and the further disintegration of these particles by the splash disc. This disintegrating action, and the desired aeration, appear to be promoted by the rapid expansion of the air escaping from the high pressure to atmospheric pressure as well as by the manner in which the air and soap are combined and discharged from the spray nozzle. The subdivision and aeration of the soap are thus effected at the outset of the cooling and dry-

ing operations, and the atomized particles of soap are then cooled and dried in their downward passage against the current of air, so that the desired degree of drying and cooling will take place. The expansion of the compressed air at the spray nozzle will assist in the cooling and drying operations.

The soap powder produced according to the present invention is made up of irregular particles which may be referred to as granulated or shredded particles. By proper regulation of the drying operation incident to the passage of the finely divided soap through the atomizing nozzle and downwardly through the drying compartment, the soap can be dried to such an extent that it requires no subsequent drying, but can be directly packaged, or directly treated for the production of soap similar to milled soap, as set forth in my said companion application.

The moisture content of the soap powder can be regulated and varied, and, as above pointed out, a soap powder can be produced having a larger moisture content than soap powders heretofore produced by mechanical means. The soap powder may thus have a moisture content of 20% or even higher, and nevertheless be free from objectionable sticking together of the particles, owing to the fact that during the drying operation they undergo a superficial or surface drying which gives a harder and drier outer surface resistant to sticking together by the ordinary pressure to which the particles are subjected. This harder and drier outer surface protects the inner and softer portions of the particles and permits them to retain an amount of moisture which very materially promotes the rapid and complete dissolving of the particles in water.

The soap particles likewise have a characteristic aerated structure, in addition to their characteristic property of having a dry and substantially non-sticking outer surface. Thus, owing to the aeration to which the soap is subjected during its disintegration, the particles are aerated, and the aerated particles are then dried and given their superficially dried surface. Aerated and dried soap particles can thus be produced which have been aerated to a sufficient degree so that the particles will readily float, and which have such a high moisture content that the particles will rapidly dissolve in water.

Where a product of greater uniformity of size than that directly obtainable by a spraying and drying operation is desired, the soap particles may be subjected to a further sieving operation to obtain different degrees of fineness.

It will be evident that the improved drying process of the present invention effects a rapid and continuous drying of soap and

that the soap can be thus converted from a hot molten state to a state of sufficient dryness for use as a soap powder or for other purposes. From another aspect, the improved process of the present invention may be considered as an aerating operation, by which hot molten soap can be aerated without the necessity for crutching. The drying and aerating operations are advantageously combined so that there is directly produced, by the atomizing and aerating operations, and the passing of the atomized product through a current of drying gas, a dried aerated soap powder.

I claim:

1. In the production of soap powder, the step which comprises effecting the disintegration and aeration of the soap by an atomizing or spraying operation, and the further step of delaying the collecting of the disintegrated particles together, until a protective skin coating is formed on said particles.

2. In the production of soap powder, the step which comprises effecting the disintegration and aeration of the soap by an atomizing or spraying operation, and the further step of skin drying the particles before they are collected together.

3. In the production of soap powder, the step which comprises subjecting hot liquid soap to an atomizing or spraying operation with compressed air and thereby effecting the disintegration and aeration of the soap, combined with the further step of passing the resulting disintegrated soap through a current of a drying gas moving in the opposite direction to the disintegrated soap whereby to dry the particles while segregated and in suspension, and collecting the resulting dried powder.

4. The method of producing soap powder, which comprises simultaneously disintegrating and aerating the soap while it is hot and molten with air under pressure, passing the disintegrated particles through a drying and cooling gas, moving in the opposite direction to the particles, whereby to delay the aggregation of the particles until a protective skin of dry soap has formed to prevent the particles from sticking when massed.

5. The method of drying soap, which comprises atomizing hot liquid soap into an atmosphere of an upwardly moving drying gas, permitting the atomizing soap to pass downwardly through such drying gas whereby to delay the aggregation of the disintegrating particles until a protective coating of dry soap has formed thereon, regulating the atomizing operation and the downward passage of the particles and the drying gas so that the soap is directly obtained as a dried product.

6. The method of drying soap, which com-

4
prises subjecting the hot liquid soap to simultaneous disintegration and aeration with a blast of air, passing the resulting soap particles downwardly through an upwardly moving current of air and regulating the force of the air current and the extent of the passage of the particles to provide the particles with protective coatings of dry

soap while they are in suspension in the air current and segregated.

7. An improved soap powder comprising aerated floating soap particles, said particles being substantially non-adherent and containing not less than about 20% of moisture.

In testimony whereof I affix my signature.
JOHN CHARAVELLE INGRAM.
